DESIGN FOR A CONTAINER

Martin M. Karlan, New York, N. Y.

Application April 26, 1939, Serial No. 84,555

Term of patent 3½ years

To all whom it may concern:

Be it known that I, Martin M. Karlan, a citizen of the United States and residing in the Borough of Bronx, county of Bronx, city and State of New York, have invented a new, original, and ornamental Design for Containers, of which the following is a specification, reference being had to the accompanying drawing, forming a part thereof in which:

Fig. 1 is a front elevational view of the container showing my new design.

Fig. 2 is a plan view of Fig. 1.

The substantially spherical element shown has a plain back face.

I claim:

The ornamental design for a container, substantially as shown and described.

MARTIN M. KARLAN.
